CRUSHER

William L. Wettlauffer, Buffalo, N. Y., assignor to
The W. S. Tyler Company, Cleveland, Ohio, a
corporation of Ohio

Application January 13, 1934, Serial No. 706,512

5 Claims. (CL. 83—53)

This invention relates to certain new and useful improvements in machines for crushing stone and like materials.

One of its objects is the provision of a crusher 5 of economical design and rugged construction, and which is capable of a large capacity and affords a maximum ratio of reduction.

Another object of the invention is to provide an efficient crushing apparatus which is so designed 10 and constructed as to produce a double crushing action and wherein the two crushing steps are so related as to operate in different phases of position of the actuating means.

A further object is the provision of crushing 15 jaws or elements which, while producing an effective crushing action, permit a continuous flow of material between them and prevent choking or clogging of the machine.

A still further object of the invention is to provide a safety release mechanism of simple construction and positive operation which automatically functions to release the crushing jaws should non-crushable material enter the machine, and which release effectually prevents damaging 20 or breakage of the machine-parts and which may be readily reset without shutting down the crusher and without added expense for broken parts.

Other features of the invention reside in the construction and arrangement of parts herein- 30 after described and particularly pointed out in the appended claims.

In the accompanying drawings:—

Figure 1 is a perspective view of a crusher embodying my invention. Figure 2 is an enlarged 35 vertical longitudinal section thereof. Figure 3 is a cross-section taken on line 3—3, Figure 2. Figure 4 is a fragmentary perspective view of a portion of the safety release mechanism. Figure 5 is a diagrammatic face view illustrating the double crushing action of my invention. Figure 6 is a fragmentary sectional view of the means employed for shutting off the flow of material to the crusher simultaneously with the release of the safety mechanism. Figure 7 is a fragmentary 40 longitudinal section, similar to Figure 2, showing a modification of the invention. Figure 8 is a cross section thereof taken on line 8—8, Figure 7.

Similar characters of reference indicate corresponding parts throughout the several views. 50 The supporting frame or base of the machine which carries the working parts of the crusher may be of any suitable construction, that shown in the drawings, by way of example, consisting of vertical side walls or plates 10 held in spaced 55 relation by any suitable means. Disposed be-

tween these side plates are opposing relatively movable crushing jaws or elements 11 and 12, respectively, which are so arranged as to form a substantially vertically-extending crushing throat 13 between them, the upper end of this throat 5 constituting the inlet for the material to be crushed and the lower end of the throat constituting the discharge for the crushed material. Intermediate the inlet and outlet ends of this throat, the material undergoes a primary and 10 secondary crushing action. The crushing element 12 is relatively movable to bring its crushing face into and out of operative crushing relation to the opposing face of the fixed crushing element.

The relatively stationary crushing element 11 is preferably so mounted that it may be readily adjustable to vary the size of the crushing throat 13 to thereby predetermine the size of the produce undergoing crushing, and for this purpose 20 the upper end of said crushing element is pivoted to a cross rod 14 supported at its ends in the side plates 10, while cooperating with its lower end is an adjusting screw 15 mounted on a supporting member or wall 16 disposed between the adjoining 25 ends of the side plates. By turning this screw in one direction or the other, the crushing element 11 is correspondingly moved toward or from the companion crusher element. If desired, a spring 11a may be employed for urging the jaw 30 toward the abutting end of the adjusting screw. The crushing element 11 has adjoining upper and lower crushing faces 17 and 18, respectively, which are preferably disposed in intersecting planes, the upper or primary crushing face 17 35 sloping downwardly and inwardly toward the face of the companion crushing element 12 and the lower or secondary crushing face sloping downwardly and outwardly, as shown in Figures 2 and 5.

The relatively movable crushing element 12 has adjoining upper and lower crushing faces 19 and 20 opposing the corresponding faces of the companion crusher element 11, such faces being preferably disposed in approximately the shape of a 40 V and substantially convex in contour. This movable crushing element is so mounted and actuated as to have a tilting or rocking movement in a vertical plane, whereby during a portion of such rocking movement its crushing face 19 moves 50 toward the opposing crushing face 17 and its crushing face 20 simultaneously moves away from the opposing crushing face 18 to effect a primary crushing action at the upper sector of the crushing throat 13 and a releasing action at 55

the lower sector of such throat to effect the discharge of the crushed material. During the remaining portion of the rocking cycle, the lower crushing face 20 moves toward the companion face of the fixed crushing element to effect a secondary or final crushing of the material to the predetermined size desired, while the upper crushing face 19 moves away from the companion crushing face 17 to permit a continuous downward feed of the material through the crushing throat. To accomplish this dual crushing action, the crushing element 12 is preferably disposed or supported intermediate its inner and outer ends between anti-friction members which may be in the form of rollers 21 journaled on a transverse rod 22 disposed between the side plates 10 and which bear against the opposing top and bottom edges or faces of the crushing element in the manner shown in Figures 2 and 5. It will be noted that the top and bottom faces of this crushing element converge outwardly and compression springs 23 are provided at the opposite sides of the crushing element 12 for urging the same outwardly against the rollers 22. As shown in Figure 1, the springs are disposed horizontally between brackets 24 and 25 secured to the sides of the movable crushing element and to the outer faces of the side plates 10, respectively. Openings 26 are provided in the side plates for accommodating the brackets 24.

The crushing element 12 is preferably actuated through the medium of a drive shaft 27 journaled in bearings 28 mounted on the side plates 10, and fixed on this shaft is an eccentric or eccentrics 29 which are connected by reciprocating connections or arms 30 with the free or rear end of such crushing element by a horizontal pivot 31. During the rotation of the drive shaft the connecting arms 30 are reciprocated vertically and to the crushing element 12 is imparted a rocking movement about an instantaneous center determined by the rollers 22. In Figure 5 is shown diagrammatically the movement imparted to the crushing element 12, the reference characters A and B indicating, for example, the limits of reciprocating travel of the connecting arm or arms 30 at its pivot 31, and the letter C indicating the instantaneous center about which the crushing element rocks. The rocking motion of the crushing element 12 imposes upon its crushing faces 19 and 20 a constant form of motion which, due to their varying radial distances from the center C, varies from point to point along those crushing faces as shown by the directional arrows arranged between the points D, E and F and D', E' and F'. As will be noticed, the various points on the crusher faces 19 and 20 change both in magnitude and direction; that is, considering the face from D to E, the magnitude of movement varies from a minimum at E-E' to a maximum at D-D' and the direction of motion is generally downward toward the opposing face 17 of the crushing element 11. From E to F, the magnitude of movement varies from a minimum at E-E' to a maximum at F-F' and the direction of motion is generally upward toward the opposing face 18 of the relatively fixed jaw. It will therefore be seen that when the upper portion of the crushing element 12 moves from D to D', the lower portion thereof moves from F' to F, thereby constituting, respectively, a crushing stroke and a releasing stroke simultaneously. Upon a vertical movement of the arm or arms 30 in the opposite direction, a reversal of the motion paths of the crushing element 12 is effected, producing a crushing

stroke from E to F in a direction from F to F' and a simultaneous releasing stroke from E to D in a direction from D' to D, and thereby providing a double crushing and releasing action during each revolution of the operation shaft 27 or during 5 each cycle. The downward rocking motion of the upper portion of the crushing element 12 augments the downward or gravity feed of the material through the crushing throat and the upward rocking motion of the lower portion of such 10 crushing element assures a positive and efficient final crushing action.

As shown in Figure 2, at the point of intersection of the crushing faces 19 and 20 there is preferably provided a transversely-extending notch, 15 indentation or relief pocket 32 which provides a partial enlargement in the crushing throat 13 and which serves thereby to ease the feed of the material from the upper sector to the lower sector of the throat and effectually prevents con- 20 gesting or clogging of the material at the transition point, or at that point where there is no appreciable component of motion perpendicular to the opposing crushing faces, and assures a continuous and uninterrupted flow of the material 25 through the crusher.

By thus constructing, mounting and actuating the crushing elements, the thrust load is absorbed by the guide rollers 22, which, because of their slow oscillating motion, are capable of withstanding heavy loads, and the eccentric shaft and associated parts are thereby relieved from the crushing loads and strains. The compression springs 23 serve to retain the crushing element 12 in its proper position and prevent backslashing of the 35 latter when the crusher is idling or running empty.

The adjustable and normally fixed, hinged crushing element 11 has preferably associated therewith a safety release mechanism which 40 functions to permit said crushing element to bodily swing away from the rocking crushing element 12 should tramp iron or similar non-crushable material find its way into the crusher, and thereby effectually and positively prevent damage or breakage to any part of the crusher. This release mechanism is so designed that it will be automatically actuated or tripped when the occasion warrants it and can be immediately reset and the hinged crushing element restored to its 50 initial position without loss of time and without shutting down the crusher. In its preferred construction shown in the drawings, this mechanism comprises the supporting member 16 upon which the adjusting screw 15 is mounted, and as shown 55 in Figures 1 and 2, this member is hinged at its upper end to a horizontal hinge pin 33 suitably supported at the left hand end of the machine-frame, whereby this member is adapted to swing vertically with the crushing element 11 at a pre-determined time, as when uncrushable material is passing through the crusher. At its lower end, this pendant or swinging member has attached thereto a transversely-disposed pivot rod or bar 34 which is disposed below the adjusting screw 60 15 and which is provided with locking lugs or shoulders 35 with which corresponding latch members 36, hinged at 37 to the side plates 10, are adapted to interlock in the normal operative 65 position of the crusher. The free or lug-engaging 70 ends of these latch members normally rest upon the top faces of the lugs. In order to adjust the latter to a proper position for a given installation, a depending arm 38 is provided substantially centrally of the pivot bar 34 and engaging this 75.

arm is an adjusting screw 39 which abuts against the outer side of the plate 16. Through the medium of this screw the pivot bar can be turned in one direction or the other to vary the position of the latch-engaging lugs 35 and thereby change the angularity or linkage between such lugs and the latch members 36 to suit a given pressure imposed upon the crushing element 11 to effect a release of such mechanism. At its ends the pivot bar may be provided with arms or extensions 40 to which suitable weights 40a may be applied and which weights determine the pressure which the latch mechanism can withstand before it is released by any abnormal pressure imposed upon the crushing element 11 when non-crushable material happens to pass through the machine. These weights also function to automatically re-set the latch mechanism after the non-crushable material has passed through the crusher throat and to restore the affected parts to their initial position.

Instead of the weighted arrangement associated with the pivot rod 34, coil springs 41 may be interposed between the free ends of the latch members 36 and brackets 42 applied to the adjoining ends of the side plates 10. And as shown in Figure 1, either or both of these arrangements may be used separately or in combination.

The hinged member 16, the pivot bar 34, and the latch members 36, constitute a releasable connection whereby a comparatively large force acting on the crushing element 11 through the adjusting screw 15 and said member 16, can be resisted by a comparatively small force acting on the pivot bar and latches. In operation, should non-crushable material enter the crushing throat 13, an abnormal outward pressure is imposed against the normally fixed crushing element 11, which will cause a relative turning of the pivot bar 34 to lift the latches 36 from the shoulders 35 and effect an uncoupling thereof, thereby automatically releasing the hinged member 16 and allowing the crushing element to swing outwardly or away from the crushing element 12 from the full line to the dotted line position shown in Figure 2, and permitting the non-crushable material to pass through the machine. The safety release mechanism can be conveniently and readily reset by merely manually swinging the member 16 inwardly until the locking shoulders 35 encounter the corresponding parts of the latches 36; when the weighted arms 40 are used, the weights thereon serve to automatically restore the mechanism to its initial latched position.

In order to prevent the material flowing on into the crusher when non-crushable material has been encountered by the crushing elements, a means may be employed to shut off or trap the material in the feed hopper 43 (see Figure 6). As shown in Figure 6, 44 indicates a sliding valve or shutter which is normally held in its open position by a vertically-swinging latch 45. This latch is operatively connected with the swinging member 16 of the safety release mechanism so that when such member is swung outwardly the latch 45 will be released and the shutter 45 will be projected to a closed position. This connection may consist of a link 46 connecting the free end of the latch 45 with an extension 47 applied to the upper end of the member 16, a spring 48 being employed for constantly urging the shutter 44 to a closed position.

In Figures 7 and 8 a slightly modified mounting for the movable crushing element is depicted, the

numeral 49 indicating the crushing jaw which is actuated in the same rocking-like manner as heretofore described, but which has a fixed fulcrum consisting of a pivot rod 50 supported in the side plates 10 of the frame and extending through the jaw at a point intermediate its ends and adjacent its crushing face 51. This face may be removably fitted in a transverse groove 52 formed in the front wall of the crushing jaw.

I claim as my invention:—

1. In a crusher, a crushing element mounted for displacement to a released position, and means for releasably retaining said element in a normally fixed position, said means including a shiftable member having a part in operative engagement with said crushing element, a latch movably mounted on a fixed support, and means on said shiftable member arranged to engage said latch and yieldably secure said shiftable member in its crushing element retaining position, said latch-engaging means being displaceable from the latch to release said shiftable member and said crushing element when an abnormal pressure is exerted on the latter.

2. In a crusher, a pivotally mounted crushing element adapted for movement to a non-crushing position when noncrushable material enters the crusher, and means for releasably retaining said element in a normally fixed crushing position, comprising a securing member pivotally mounted on a fixed support and disposed adjacent the outer side of the crushing element and having a part in engagement therewith, a latch member movably mounted on a fixed support, and a pivot bar mounted on said securing member and having a locking shoulder thereon with which said latch normally engages.

3. In a crusher, opposing relatively movable crusher elements disposed to form a crushing throat therebetween, one of said elements provided with a rearwardly extending supporting and actuating arm, anti-friction guiding and supporting means engaging opposite faces of said arm between its ends and means for imparting a rocking movement to said arm whereby the paths of the various points on the face of the crusher elements carried thereby vary in both magnitude and direction relative to the face of the companion crushing element.

4. In a crusher, opposing relatively movable crusher elements disposed to form a crushing throat therebetween, one of said crusher elements extending horizontally and provided with a substantially vertically arranged working face, anti-friction guiding and supporting means engaging said last-named element on the top and bottom surfaces thereof intermediately its ends, and means for imparting a rocking movement to said last-named crusher element whereby the paths of the various points on its said working face vary in both magnitude and direction relative to the face of the companion crushing element.

5. In a crusher, a releasable crushing element, means normally retaining said element in a fixed crushing position, resettable means governed by an excess of pressure imposed upon said crushing element for automatically releasing said retaining means, a gate arranged for movement across the stream of material to be crushed, means urging said gate to a closed position, a catch for securing said gate in an open position, and means functionally responsive to release of said first-named retaining means for releasing said catch.
